UNITED STATES PATENT OFFICE

GUSTAV OSCAR NILSSON BRANDBERG, OF SIOUX FALLS, SOUTH DAKOTA.

COVER.

Application filed November 4, 1922. Serial No. 599,169.

This invention relates to upholstery for seats, the general object of the invention being to provide means for assembling and disassembling the parts so that new parts can be substituted whenever necessary or the old parts taken off and cleaned or repaired and replaced.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of a seat constructed in accordance with this invention.

Figure 2 is a longitudinal sectional view through Figure 1.

Figure 3 is a fragmentary plan view of the upper part of the spring frame.

Figure 4 is a similar view of the lower part of the spring frame.

Figure 5 is a fragmentary perspective view with parts in section, and showing an extension at the front side.

Figure 6 is a similar view showing a fringed extension.

Figure 7 is a sectional view showing the invention in use.

Figure 8 is a detail view of one of the springs.

Figures 9 and 10 are detail views of a slide and its guideway.

As shown in these views the bottom support A for the springs 1 is composed of a number of longitudinally and transversely arranged channel strips 2, the strips being preferably connected together by the tongues 3 which are cut from portions 3' formed from the side walls of the transversely arranged strips 2' and bent upon the longitudinally arranged strips 2 as clearly shown in Figure 4 of the drawings. These mentioned portions 3' of the transverse strips are bent at right angles to the main portions thereof to allow the respective strips to be arranged flush with each other and crossed and secured in the manner as set forth. Adjacent the intersections of the strips notches 4 are formed for receiving the lower ends of the springs. A hook 5 is placed at the

center of the junction of the strips and gutters 7 are connected with the ends of the strips, preferably by having the said ends curving upwardly to grip the gutters, as shown at 8. The top member B is composed of the side plates 9 which are connected together and which are provided with tongues 13 which are bent downwardly over the upper ends of the outer springs. A wire 14 or the like passes through each spring and has one end connected with a hook 5 and its other end with a cross piece 15 which is connected with the top of the spring. The plates 9 are formed with the cross pieces 15' for receiving the wires 14 of the outer springs. This arrangement of parts limits the expansive movements of the springs. A cushion C is placed on the member B and a second cushion D is placed on the first cushion, the cloth forming the covers of this second cushion extending down into the gutters where it is held by rods 16 passing through loops formed in the cloth, thus holding the cloth in the gutters. When the cushions are to be removed it is simply necessary to pull out the rod 16 in order to free the side parts 17 of the covers which will permit the covers and cushions to be removed.

Figure 5 shows an extension 18 formed on the front edge of the gutter which acts to hide the gutter and the parts associated therewith. In Figure 6 the extension 18' is a part of the side pieces of the covers and this extension may be provided with a fringe as shown at 19.

Figure 7 shows a seat, the seat and back cushions of which are constructed in accordance with my invention. The cushion parts are detachably secured to the seat and back parts by means of the slides 20 which are attached to the cushion parts and the guideways 21 which are attached to the supporting parts and which the slides 20 engage. The slides are locked in the guideways by means of the spring latches 22. The back cushion has the upper ends of its channel members bent over to engage the upper edge of the back of the seat, as shown at 23, and the top gutter is provided with an extension 24 which overlaps the part 23 and has its outer edge bent downwardly into engagement with the rear part of the seat back. In this Figure 7 the seat cushion has both its outer gutter and its channel members provided with extensions 25 which

extend downwardly so as to hide the gutter parts and the junction at the front edge of the seat support.

From the foregoing it will be seen that 5 the parts of the seat can easily be taken apart for cleaning or repairing.

It is thought from the foregoing description that the advantages and novel features of my invention will be readily apparent. 10 I desire it to be understood that I may make changes in the construction and in the combination and arrangement of the several parts, provided that such changes fall within the scope of the appended claim.

What I claim is:—

In a seat, a frame including pairs of channel shaped members arranged in crossed relation and formed with notches in the

upper portions of their side walls adjacent 20 their points of crossing, tongues formed on some of said notched portions and clamped in a manner to provide a means for securing said pairs of channel shaped members in operative association, a seat element arranged above the frame, springs interposed between the seat element and frame respectively, said springs having their base convolutions received in said notches, a cross pin secured to the upper convolution of 30 each spring, a hook secured centrally at the juncture of the cross members, and rods depending from the cross pins and passing through the springs and anchored to the hooks. 35

In testimony whereof I affix my signature.

GUSTAV OSCAR NILSSON BRANDBERG.
